UNITED STATES PATENT OFFICE.

JOHN ROBERT SPENCE AND JAMES LESLIE BOSS, OF BARTOW, FLORIDA.

SLICER, GRATER, AND SHREDDER.

1,205,052.

Specification of Letters Patent. Patented Nov. 14, 1916.

Application filed April 6, 1915. Serial No. 19,508.

To all whom it may concern:

Be it known that we, JOHN ROBERT SPENCER and JAMES LESLIE BOSS, citizens of the United States, residing at Bartow, in the county of Polk and State of Florida, have invented new and useful Improvements in Slicers, Graters, and Shredders, of which the following is a specification.

This invention is an improved machine for slicing, grating and shredding vegetables, fruits and the like and adapted for household, restaurant and hotel use and also adapted for use in other places, the object of the invention being to provide an improved machine of this character which is provided with a series of interchangeable cylinders each adapted for doing a different kind of work, so that the same machine may be used for slicing, grating and shredding.

The invention consists in the construction, combination, and arrangement of devices hereinafter described and claimed.

In the accompanying drawings:—Figure 1 is a perspective view of a machine constructed in accordance with our invention, showing the same with the slicing cylinder in place and with the follower lid raised. Fig. 2 is a transverse sectional view of the same with the rotary stripping cylinder in place. Fig. 3 is a longitudinal sectional view of the same with the combined grating and shredding cylinder in place.

In accordance with our invention we provide a suitable base 1 on which is secured a metal plate 2 said metal plate being formed with upturned side portions 3 and with an upturned rear flange or wall 4. We also provide a reinforcing piece 6 which is bent to form side members 7 and a rear wall 8. Said wall 8 is secured to the rear wall of the plate 2 and said side members are secured to the side pieces of said plate and co-act therewith to form standards each of which has a bearing opening 9 and an inclined slot 10 leading to said bearing opening. The upper ends of the standards are semi-circular in form or substantially so and each standard is provided on its outer side with a catch 11 which is pivoted as at 50 12 and has a slot 13 concentric with its pivot.

The rear wall has an outturned roll 14 at its upper edge. A substantially semitubular follower and cover plate 15 is hinged at its lower edge on a rod 16 between the standards, at a point slightly in front of the rear wall. Said follower and cover plate has

stops 17 at its ends and also has a finger piece 18. Conical hollow teeth or studs 19 are formed on the inner side of the follower or cover plate by punching the same from the outer side.

We also provide a series of interchangeable cylinders for co-action with the cover and follower plate in slicing, shredding or grating fruits, vegetables or the like, these cylinders being interchangeable so that any one of them may be mounted on the supporting frame formed by the plate and reinforcing member and used in connection with the follower and cover plate.

The cylinder 21 is for slicing and is formed with diagonal slots 25 the outer sides of which are formed by diagonal cutting edges 27. One end of the said cylinder is closed by a head 28 which has a trunnion 29 adapted to be mounted in the bearing opening of one of the standards, and squared for engagement by a crank 30 whereby said cylinder may be rotated. The other end of the cylinder is closed by a removable cover 31 which has a trunnion 32 adapted to be mounted in the other bearing. The catches may be turned upwardly to engage their slots with the trunnions of the cylinder so as to hold the latter in its bearings. The material to be sliced is placed on the cylinder and gets pressed against the same by pushing downwardly on the follower and the cover plate. The cylinder is revolved in the required direction to cause its diagonal cutting edges to cut the material in slices which passes inwardly through the diagonal slots into the cylinder. When the material has been thus sliced the follower and cover plate is raised, the catches disengaged from the trunnions, the cylinder is raised and moved from its bearings and the removable cover in one end of the cylinder is removed therefrom, thus enabling the sliced material to be taken out of the cylinder. Any one of the cylinders may be used in this manner in connection with the supporting frame and cover plate and follower. The cylinder 33 is formed with small peripheral cutting knives 34 and with openings 35 under said knives and is for stripping. The cylinder 36 has one-half of its peripheral surface provided with outstruck hollow conical grating studs 37 and the other half of its peripheral surface provided with small outstruck substantially triangular grating teeth 38.

22
Any suitable number of cylinders may be interchangeably used in my machine and may be provided with any suitable kinds of teeth or other devices according to the nature of the work desired.

The machine may also be made of any suitable size and shape and of any suitable material.

Having thus described our invention we 10 claim:—

A machine of the class described comprising a pair of spaced standards, a toothed cylinder journaled in the standards, an ar-

cuate shaped resilient follower swingingly mounted between the standards, and stops formed upon the medial portion of the follower and engageable with the cylinder to limit the inward movement of the follower.

In testimony whereof we affix our signatures in presence of two witnesses.

JOHN ROBERT SPENCER.
JAMES LESLIE ROSS.
